UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

TERMINAL FOR HEATING ELEMENTS.

Application filed August 30, 1923. Serial No. 660,123.

To all whom it may concern:

Be it known that I, ORA A. COLBY, a citizen of the United States, and a resident of Irwin, in the county of Westmoreland and 5 State of Pennsylvania, have invented a new and useful Improvement in Terminals for Heating Elements, of which the following is a specification.

My invention relates to electrically heated 10 devices and particularly to terminals for the heating elements of electric irons.

The object of my invention is to provide a relatively simple, compact and easily manufactured and assembled terminal structure 15 for an armored electric heating element.

In practicing my invention, I provide an electric heating unit comprising a resistor located within a plurality of metal plates constituting a casing for the resistor. Terminal pins are mounted on sheet metal terminal-supporting members, of substantially L-shape, that are insulatedly supported on the heating unit by co-operating notches and shoulders that hold the terminal supporting 20 members in their proper operative positions relatively to the heating unit and prevents lateral and longitudinal movement thereof relatively to the heating unit.

In the single sheet of drawings, 30 Figure 1 is a view, partially in side elevation and partially in vertical longitudinal section, through an electric iron embodying my invention,

Fig. 2 is a top plan view of an encased 35 electric heating unit embodying my invention,

Fig. 3 is a view in rear elevation thereof,

Fig. 4 is a partial view, in combined side elevation and longitudinal section, of a device 40 embodying my invention, and

Fig. 5 is a partial view, in combined side elevation and longitudinal section, of a modified form of device embodying my invention.

An electric iron 11 comprises a sole or 45 bottom plate 12, an encased heating unit 13, a top plate 14 and a cover member 15. The sole plate 12, heating unit 13 and the top plate 14 constitute what may be termed the body portion of the iron. The top plate 14 is held in its proper operative position 50 against the upper surface of the heating unit 13 by any suitable means, such as a machine screw 16, extending through the top plate and the heating unit and into the bot-

tom plate. The cover member 15 is held in its proper operative position against the upper surface of the sole plate 12 by a relatively heavy machine bolt 17 extending into the sole plate 12. 60

A handle member 18 is mounted at the upper ends of a handle strap member 19, of substantially U-shape, that has its intermediate portion secured against the upper surface of the cover member 15 by a plurality of rivets 21. 65

The encased heating unit 13 comprises a lower sheet metal member 22 and an upper sheet metal member 23, between which is located an electric heating element 24 that 70 may comprise a suitable metallic resistor member located on a sheet of electric-insulating material, and which is insulated from the top and the bottom plates by sheets 25 of a suitable electric insulating material, such 75 as mica. The lower plate 22 has upwardly extending and inturned peripheral flange portions 26 to permit of tightly clamping the upper plate 23 against the heating element 24. While I have illustrated a particular 80 outline of encased heating unit 13, here shown as substantially triangular in shape, the device embodying my invention is not limited thereto and any particular shape 85 may be employed.

Terminal pins 27 are mounted on terminal-supporting members 28 that may comprise two parts 28 and 28a or, if considered desirable, the two parts 28 and 28a may be made integral with each other. The member 28 comprises a short sheet-metal member, of substantially L-shape, provided with an opening into which the lower end of the pin 27 may extend and be secured therein as by riveting over the projecting end portion 90 thereof. The member 28a is also of substantially L-section and is secured to the lower end of the member 28 by a machine screw 29. 95

As illustrated more particularly in Fig. 4, of the drawing, the top metal sheet 23 is provided with a pair of spaced, aligned and laterally extending openings 31 comprising a notch to co-operate with a shoulder portion 32 of the members 28a. The shoulder portions 32 may be formed by suitably bending a part of the members 28a. Small sheets 33 of insulating material, such as mica, are employed to insulate the metal members 28a from the top plate 23 and from the heating element 24. 100 105 110

The ends 34 of the resistor member comprising a part of the heating unit 24, are secured against the members 28a by the machine screws 29, so that the terminal pins 27 are electrically connected to the resistor.

Fig. 5 of the drawings illustrates a modified form of construction in which the member 28a is provided with a notched portion 35 and both the top plate 23 and the bottom plate 22 are provided with co-operating shoulder portions 36, that extend into the notches 35 of the members 28a to hold them in their proper operative positions relatively to the heating unit. Sheets 33 of electric insulating material are provided, as hereinbefore described, to insulate the members 28a from the top plate and the heating element 24.

An elongated opening 37 is provided at the rear of the cover member 15 through which the terminal pins 27 may extend, a block 38 of a suitable refractory electric insulating material being provided through which the pins 27 may project in order to hold the pins 27 and the members 28 and 28a in their proper operative positions within the assembled iron.

The device embodying my invention provides a relatively simple and compact means for holding the terminal member in its proper operative position relatively to the heating element, with which it is associated, and with a part of which it is interlocked.

Various modifications and changes may be made without departing from the spirit

and scope of the invention, I desire, therefore, that only such limitations shall be imposed thereon as are indicated by the prior art or set forth in the appended claims.

I claim as my invention:

1. In an electric heating unit for an electrically heated device, in combination, a metal bottom plate, a metal top plate, an electric heating element located therebetween, and a terminal-member-supporting means having a portion extending between said top and bottom plates and interlocked with said top plate. 40

2. In an electric heating unit, in combination, an electric heating element, a metal casing surrounding said heating element, terminal pins, and terminal pin supports carried by said heating unit, said casing and said supports having co-operating notches and shoulders for securing said supports in their proper operative positions relatively to said metal casing. 50

3. In an electric heating unit, in combination, an electric heating element, a metal casing surrounding said heating element, terminal pins, and terminal pin supports, said casing and supports having co-operating notches and shoulders for preventing both lateral and longitudinal movement of said supports relatively to said casing. 60

In testimony whereof, I have hereunto subscribed my name this 23rd day of August 1923.

ORA A. COLBY.
